UNITED STATES PATENT OFFICE.

JOHN W. HANLEY, OF NEW YORK, N. Y.

DESIGN FOR A GAME BOARD.

Application filed March 28, 1923. Serial No. 5,620. Term of patent 14 years.

To all whom it may concern:

Be it known that I, JOHN W. HANLEY, a citizen of the United States, and a resident of the city of New York, borough of Manhattan, in the county and State of New York, have invented a new, original, and ornamental Design for Game Board, of which the following is a full, clear, and exact description.

The figure is a plan view of the game board constructed and arranged in accordance with the design.

I claim:

The ornamental design for a game board, as shown.

JOHN W. HANLEY.
